J. BASILE.

BEDSTEAD,

APPLICATION FILED MAR. 21, 1921.

1,391,448.

Patented Sept. 20, 1921.

Inventor:

JOSEPH BASILE

Attorney,

၁၃၅

UNITED STATES PATENT OFFICE.

JOSEPH BASILE, OF NEW YORK, N. Y., ASSIGNOR, BY DIRECT AND MESNE ASSIGNMENTS, OF ONE-HALF TO GREENPOINT METALLIC BED COMPANY, OF BROOKLYN, NEW YORK, A FIRM COMPOSED OF DAVID FRANK, JOHN TROUNSTINE, AND WILLIAM LIES, AND ONE-HALF TO JOSEPH TURK MANUFACTURING CO., OF BRADLEY, ILLINOIS, A CORPORATION OF ILLINOIS.

BEDSTEAD.

1,391,448.

Specification of Letters Patent. Patented Sept. 20, 1921.

Application filed March 21, 1921. Serial No. 453,947.

To all whom it may concern:

Be it known that I, JOSEPH BASILE, a subject of the King of Italy, and a resident of New York city, in the county of New York and State of New York, have invented certain new and useful Improvements in Bedsteads, of which the following is a specification.

The invention relates to improvements in metal bedsteads, and it has reference more particularly to the corner fastenings thereof or the means by which the main bed-frame or mattress section is detachably connected at its corners with the posts of the head and foot frames. The head and foot frames have tubular corner posts which are preferably square or rectangular in cross-section, and these posts are each equipped with two rigid slotted hook-members, one being adapted to receive the lower end of the vertical outer portion of the end rails of the main frame, and the other being offset inwardly from the inner edge of the post and adapted to receive the vertical flange of the end rail adjacent to the vertical end portion of said rail. The end rails of the main frame are connected by angle-iron side rails and receive the ends of the spring or metallic mattress, and said end rails are formed of angle iron and comprise a transverse rail portion and downwardly extending end portions, the lower ends of said end portions being supported in and held by the lower hook-members of the corner posts, and said rail portions having their vertical flange, inwardly from the said end portions, caught within and held by the upper hook members secured to the corner posts.

My invention seeks to provide a very simple and durable three-piece bed construction and one in which the mattress supporting frame may be very readily and securely connected with and separated from the head and foot frames of the bedstead.

The invention will be fully understood from the detailed description hereinafter presented, reference being had to the accompanying drawings, in which:

Figure 1 is a vertical transverse section, partly broken away, through a three-piece bedstead constructed in accordance with and embodying the invention;

Fig. 2 is a side elevation, partly broken away and partly in section on the dotted line 2-2 of Fig. 3, of the same;

55

Fig. 3 is a horizontal section, partly broken away and taken on the dotted line 3-3 of Fig. 2, of the same, and

Fig. 4 illustrates a portion of the corner post and a portion of the mattress supporting frame ready to be assembled, the mattress supporting frame to be applied upon the hook corner fastening members shown as carried by the corner post.

In the drawings, 10 designates a head or 65 foot frame, both being alike, having corner posts 11 and suitable connecting bars, as 12, as usual, said corner posts being tubular and preferably square in cross-section. Each corner post of the head and foot frames has 70 secured to it an upper hook or fastening member 13 and a lower hook or fastening member 14, as illustrated in Fig. 4, said members 13, 14 each being formed of a piece of iron bent at a right angle to form 75 a front section 15 and a plate base section 16. The front section 15 of the upper member 13 is formed with a vertical transverse recess or slot 17, and the front member 15 of the lower fastening member 14 is formed 80 with a transverse recess or slot 18, said slots corresponding with each other and being open at their upper ends. The plate members 16 of the corner fastenings 13, 14 are secured by spot welding against the inner face 85 of the corner-posts 11 of the head and foot frames, the spot welding being indicated at 19. For the purpose of greater security and durability of construction I apply within the tubular corner-posts and in line with the 90 plate members 16 of the corner fastenings, a vertical plate 20 and, by means of the spot welding secure said plate, post and plate members 16 together.

The fastening members 13, 14 are of hook 95 character and employed for supporting and securely holding the mattress frame member of the bedstead, as hereinafter explained. At each corner-post 11 the hook-members 15 of the corner fastenings extend longitudinally of the bedstead, and at each of said posts the member 15 of the upper corner fastening 13 is offset inwardly so as to extend inwardly beyond the post with which it is

connected, as clearly represented in Figs. 1, 3 and 4, and this inwardly offsetting of the engaging member of the upper corner fastening is for the purpose of securing important mechanical effects.

The spring or the mattress supporting member of the bedstead is composed of two angle-iron side rails 21 and two end frames 22 which are of angle iron shape in cross-section and composed of a transverse end rail 23 and vertical members 24 which are integral with and project downwardly from the ends of the end rails 23. The vertical members 24 of the end frames 22 are secured by rivets 25 to the side rails 21 and are connected also by inclined braces 26 with said side rails, said braces 26 being riveted at 27 to the inner face of the side flange of the vertical members 24 and thence being extended downwardly through slots 28 in the side rails 21 and secured by rivets 29 to the inner face of the vertical side flanges of said side rails. The ends of the braces 26 are in the construction described concealed and said braces serve to materially strengthen the connection of the end frames 22 to the side rails 21. The horizontal flanges of the end frames 22 receive the usual helicals 30 of the metallic spring or mattress, as usual. My invention does not pertain to the helicals 30 or to the character of spring mattress, but to the end frames 22 and the co-operative means provided therefor and represented by the fastening members 13, 14, secured to the corner posts.

In assembling the head and foot frames 10 and main bed or mattress carrying frame, the lower ends of the end members 24 of the end frames 22 are inserted downwardly into the recesses 18 of the lower corner fastening members 14, as shown, and the vertical flange of the end frames 22 adjacent to the inner vertical edges of the end members 24 are inserted downwardly into the recesses 17 of the upper corner fastenings 13, whereby the mattress frame composed of the side rails 21 and end frames 22, becomes supported at the lower ends of the members 24 of the end frames and at the ends of the transverse vertical flanges of said end frames adjacent to the vertical members 24. The corner fastenings 13, 14 are each in one integral rigid piece and, arranged as described, rigidly support the mattress carrying frame and permit of the ready assembly of said frame with the head and foot frames. The construction of bed presented by me is one of great durability and capable of ready construction, and the parts thereof may be readily assembled and disassembled without undue effort.

I may call attention to the fact that in equipping the post with the hook members 13, 14 of the character described, there is no cutting away or weakening of the post, but

instead the post is rendered more durable by the presence of the bar 20 and base members 16 of the corner fastenings. It is also obvious that the main bed frame or spring-carrying member becomes very securely supported by the hook members 13, 14, the weight of said member being equally divided between the members 13, 14, and said members, by reason of their hook formation, affording very strong supports and firmly holding the main bed member against lateral or endwise movement.

What I claim as my invention and desire to secure by Letters Patent, is:

1. A bedstead comprising head and foot frames and a main mattress supporting frame consisting of side rails and end rails having at their ends downwardly extending members secured to said side rails, said head and foot frames having corner posts and upper and lower hook members secured to said posts, the lower hook members being slotted vertically to receive and support the lower ends of said downwardly extending members of said end rails and said upper hook members being offset from the sides of the posts and slotted to receive the end portions of said end rails adjacent to the inner edges of said downwardly extending members thereof. 95

2. A bedstead comprising head and foot frames, a main mattress supporting frame consisting of angle iron side rails and end rails having at their ends downwardly extending members riveted to the ends of said side rails and braces riveted to the inner faces of the upper ends of said downwardly extending members and to the inner faces of said side rails, the upper flanges of said side rails being slotted to admit the lower ends of said braces, said head and foot frames having corner posts and upper and lower hook members secured to said posts, the lower hook members being slotted vertically to receive and support the lower ends of said downwardly extending members of said end rails and said upper hook members being offset from the sides of the posts and slotted to receive the end portions of said end rails adjacent to the inner edges of said downwardly extending members thereof. 110

3. A bedstead comprising head and foot frames and a main mattress supporting frame consisting of side rails and end rails having at their ends downwardly extending members secured to said side rails, said head and foot frames having corner posts and upper and lower corner fastening members secured to said posts, the lower fastening members being adapted to receive and support the lower ends of said downwardly extending members of said end rails and said upper fastening members being offset from the sides of the posts and slotted to 130

receive the end portions of said end rails adjacent to the inner edges of said downwardly extending members thereof.

4. A bedstead comprising head and foot frames and a main mattress supporting frame consisting of side rails and end rails having at their ends downwardly extending members secured to said side rails, said head and foot frames having corner posts and upper and lower members secured to said posts, the lower members being recessed

to receive the lower ends of said downwardly extending members of said end rails and the upper members being offset from the sides of the posts and recessed to receive 15 the end portions of said end rails adjacent to the inner edges of said downwardly extending members thereof.

Signed at Brooklyn, in the county of Kings and State of New York, this 18th day 20 of March, A. D. 1921.

JOSEPH BASILE.
